[57] CLAIM

The ornamental design for a computer terminal workstation, substantially as shown and described.

DESCRIPTION

FIG. 1 is a perspective view of a computer terminal workstation showing our new design;

FIG. 2 is a front elevational view thereof;

FIG. 3 is a back elevational view thereof;

FIG. 4 is a top plan elevational view thereof; and

FIG. 5 is a side elevational view thereof.

The side of the computer terminal workstation not shown is a mirror image of the side shown in FIG. 5.

*Fig. 1.**Fig. 2.**Fig. 3.*Fig. 4.

Fig. 5.
